CONTAINER FOR MUSHROOMS AND OTHER PRODUCE

Michael A. Tishuk, Hackettstown, N.J., assignor to United States Mineral Products Company, Stanhope, N.J., a corporation of New Jersey

Filed July 12, 1967, Ser. No. 7,781

Term of patent 14 years

(Cl. D9—224)

FIG.3

FIG.4

FIG.5

FIG.6

FIG.7

FIG. 1 is an exploded perspective view of the container for mushrooms and other produce showing my new design.

FIG. 2 is a side-elevational view thereof with the cover and handle in position.

FIG. 3 is a bottom plan view thereof showing my new design.

FIG. 4 is a top plan view of the inside thereof with the cover and handle removed.

FIG. 5 is a sectional view taken along line 5—5 of FIG. 2.

FIG. 6 is a sectional view taken along line 6—6 of FIG. 5.

FIG. 7 is a plan view of the inside of the cover thereof. I claim:

The ornamental design for a container for mushrooms and other produce, as shown.
